U.S. Cl. D10—111

FIG. 1

FIG. 2

FIG. 3

FIG. 1 is a front-elevational view of a reflector incorporating my new design;

FIG. 2 is a top-plan view of the reflector of FIG. 1; and
FIG. 3 is a rear-elevational view of the reflector of
FIG. 1.

The cross hatching in FIG. 1 represents retroreflective elements which are visible over substantially the entire front of the reflector. The cross hatching is divided into three areas to signify that the inclination of elements in one area differs from that in the other areas.

I claim:

The ornamental design for a reflector, substantially as shown and described.
